Primary Examiner — Michelle E. Wilson*Assistant Examiner* — Charles Hwang(74) *Attorney, Agent, or Firm* — David E. Crawford; Fast Forward Law, LLC(57) **CLAIM**

The ornamental design for a power storage enclosure as shown and described.

DESCRIPTION

FIG. 1 is a first perspective of a power storage enclosure; FIG. 2 is a second perspective of said enclosure; FIG. 3 is a front elevation of said enclosure; FIG. 4 is a rear elevation of said enclosure; FIG. 5 is a right side elevation of said enclosure; FIG. 6 is a left side elevation of said enclosure; FIG. 7 is a top plan of said enclosure; FIG. 8 is a bottom plan of said enclosure; FIG. 9 is a first separated perspective of said enclosure; FIG. 10 is a second separated perspective of said enclosure; FIG. 11 is a perspective of a mount portion of said enclosure; and, FIG. 12 is a front elevation of said mount portion. The broken lines used throughout the drawing disclosure are for the purposes of illustrating interior and environmental portions of the power storage enclosure and form no part of the claimed design.
